UNITED STATES PATENT OFFICE.

YUKINOBU YAMAMOTO, OF ST. LOUIS, MISSOURI.

SHADE.

1,140,092.

Specification of Letters Patent.

Patented May 18, 1915.

Application filed February 26, 1915. Serial No. 10,662.

To all whom it may concern:

Be it known that I, YUKINOBU YAMAMOTO, a subject of the Emperor of Japan, residing at the city of St. Louis, State of Missouri, have invented certain new and useful Improvements in Shades, of which the following is a specification.

This invention relates to improvements in shades and has for its object to provide a shade of cheap and simple construction adapted to be propelled rotatively upon a bearing by means of the heat of the light shaded by the shade, and adapted, also, to be adjustably locked against rotation while shading said light.

An advantage of a shade embodying the present invention is that it provides a device of the character described that is light in weight, attractive in appearance, easily operated, and adapted to be used in connection with electric lights, candle lights, or other lights, and which may be permitted to rotate or prevented from rotating at will, while shading said light.

Further, the present invention consists in the novel features of construction, arrangement, and combination of parts described in this specification and pointed out in the claims.

In the accompanying drawings, forming part of this specification, wherein like numbers of reference denote like parts wherever they occur, Figure 1 is a plan view looking downwardly upon the top of a shade embodying the present invention; Fig. 2 is a vertical sectional view of a shade embodying the present invention in connection with a candle, and showing means for shielding the top of the shade from the flame of the candle; Fig. 3 is a detailed plan view on an enlarged scale looking upwardly into the bearing borne by the top of the shade; Fig. 4 is a sectional view on an enlarged scale showing in detail the flame-shield of Fig. 2 and parts associated with said flame-shield, and showing, also, an enlarged detailed view of the adjustable locking and braking device for stopping the rotative motion of the shade when in place over a burning light;

Fig. 5 is a vertical sectional view of a modified form of a shade embodying the present invention in use in connection with an electric light bulb; Fig. 6 is a plan view, on an enlarged scale, looking downwardly on a fragment of the top of the shade, and showing an alternate form of a brake associated

with said top; and Fig. 7 is a view of Fig. 6 partly in elevation and partly in section, showing, also, a fragment of an axial support for the shade.

Top 1 may be made of any suitable material, such, for instance, as card-board, and may be circular in shape, as shown in the accompanying drawings, or may be of any other suitable shape. Side-portions or skirt 2 borne by said top may be secured thereto in any suitable manner or by any suitable means, such, for instance, as by means of being glued or pasted to the adjacent outer edge of said top, and may extend below said top for a distance sufficient to shade the light associated therewith, such, for instance, as the light of a candle 3 or electric bulb 4. Said skirt 2 may, also, if desired, extend slightly above said top 1, as best seen in Figs. 75 2 and 5, said extension above said top being adapted, for instance, for screening from observation parts hereinafter described associated with said top.

An opening 5 may be provided in top 1, said opening being preferably centrally located relative to the outer edge of said top, and a plurality of propeller blades 6 may be arranged substantially radially the axis of rotation of the shade and may be formed integrally with top 1, as shown in Figs. 1 and 2, or may be formed integrally with skirt 2, as shown in Fig. 5 of the accompanying drawings, each blade 6 being preferably formed by making an appropriate incision in said top or skirt and bending a portion of the material adjacent said incision outwardly to present a protruding surface to serve as a suitable propeller-blade adapted for the purpose hereinafter described in a shade embodying the present invention, there being an opening 7 adjacent each blade 6, and a straight line defining the attached edge of each blade and drawn from one end to the other of each incision made to form a blade preferably lying obliquely to the radial planes radiating from the axis of rotation of the shade.

Skirt 2 may be made of any suitable material, but is preferably made of a more or less translucent material of light weight, such, for instance, as paper, thin silk, sheer cloth, or the like, adapted to shade the light of the flame of candle 3, electric bulb 4, or the like without entirely obscuring the rays of said light, and said skirt 2 may be of any desired shape in vertical elevation, but pref-

erably has the shape, in vertical elevation, of a cone, a pyramidal figure, or the like with the peak thereof cut away transversely the height of said figure.

5 A cap 8 having a rim, as best seen in Fig. 4, may be made of any suitable metal or other material, and is adapted to cap opening 5 to provide means for supporting a shade embodying the present invention as 10 hereinafter described, the peak of said cap extending above the upper surface of top 1 and presenting its bowl or concavity downwardly over said opening 5, said cap being preferably secured to said top by means of 15 an annular member 9 bearing a plurality of prongs 10 depending therefrom, said annular member being adapted to fit over the peak of said cap and to overlap upon the rim thereof, prongs 10 being adapted to 20 pass through said top 1 and to be clamped against the surface of the reverse side of said top. Cap 8 is preferably constructed of hardened metal to provide a suitable and substantial bearing of great durability 25 against wear by friction with parts herein- after described. Annular member 9 together with its depending prongs 10 formed integrally therewith being preferably made of thin pliable material, such, for instance, 30 as thin metal, prongs 10 being preferably adapted to be bent upwardly against the inner surface of top 1, as shown in the drawings herewith, for the purpose of holding said cap 8 in place, the points of said prongs 35 being adapted to perforate said top prior to the passing through said top and prior to bending said prongs over against the said inner surface of said top.

Brake device 11 may be made of a piece 40 of spring wire, said wire being bent upon itself to form a loop-shaped upwardly protruding finger-piece 12 at one end, the other end being pivoted at 13 to said top 1, said pivotal attachment with said top being of 45 any suitable construction, such, for instance, as by means of piercing said top with said end of said wire and crimping or pressing a portion adjacent said end over against the upper surface of said top, as shown in the 50 accompanying drawing, said pivotal connection being preferably located near the outer edge of said top on an axis of a circle described about the center of said opening 5, and said brake device being adapted to 55 extend along the under side of said top from said pivotal connection across the portion of said top bearing cap 8 and annular member 9, thence to a convenient location on the other side of said cap 8 and said member 9, 60 at which location said loop-shaped finger- piece 12 may protrude upwardly above the upper surface of said top through an appropriate opening 14 therefor formed in said top 1, said opening having the edge of 65 one side preferably along the line of an axis

of a circle centering in the center of said opening 5, said line being in such position so that said side of said opening may be adapted to engage a portion of said finger-piece to limit the movement thereof to prevent the portion of said brake device beneath said top from crossing the axis of rotation of said shade, the opposite side of said opening 14 having its edge so located as to be adapted to limit the movement of 70 said brake device in a direction away from said axis of rotation, the side of said opening 14 nearest annular member 9 being adapted to engage adjacent portions of the loop of said finger-piece 12 to lock said braking device in any set position by means of the spring-pressure of said loop-shaped finger-piece against said adjacent side of said opening.

An alternate form of brake device 11 is 85 shown in Figs. 6 and 7 of the accompanying drawings. In said alternate form, said brake device may be made of a plate 11 having one end pivotally attached at 13 to said top 1 in any suitable manner, such, for instance, as by means of the arrangement of parts shown in said Figs. 6 and 7 wherein said end of said plate is pivotally attached to said top by means of one of the prongs 10 of annular member 9. The free end of said brake may be adapted to protrude beyond the outer edge of said annular member and relatively opposite said pivotal attachment, said annular member being preferably supported slightly spaced away from 90 the surface of said top by means of said prongs, said free end being preferably provided with a finger-piece 12 of any suitable construction, adapted for conveniently operating said brake device.

The two prongs 10 adjacent said free end of plate 11 are so disposed relative to the swing of said free end and said plate on its pivotal attachment 13 so that one prong 10 will limit the movement of plate 11 toward the center of cap 8 and toward the axial support of the shade, and so that the other prong 10 will limit the movement of plate 11 away from said center and away from 110 said axial support, said limitings of said movement being effected by the engagement of portions of said plate adjacent said free end with said prongs. Said plate may be provided with a notch adjacent said axial support for the purpose of providing a 115 greater frictional bearing for more efficient braking service, as shown in said Fig. 6.

Shield-plate 15 may be constructed of any suitable material and may be of any suitable shape, but is preferably a metal disk adapted to shield top 1 from the flame of a light such as that of candle 3, said shield-plate bearing on its under side, supporting member 16, said supporting member bearing depending flange 17, which flange is adapted 120

to rest inside the annular band 18 of an ordinary shade-supporting standard usually employed for supporting a candle-shade of an ordinary construction, flange 17 being adjacent the inside of annular band 18 and being adapted to seat within said band, the upper edge of said band abutting upon the under surface of said member 16. A pin 20 having a head 21 and a pointed end 22 may be inserted through an appropriate opening therefor formed in member 16 and shield-plate 15, the point 22 of said pin protruding upwardly above said shield-plate, and the head 21 being adjacent the under surface of said shield-plate and being adapted to support said member 16 adjacent the under surface of said shield-plate, and for more securely attaching supporting member 16 and shield-plate 15 together, said pin 20 may be provided with a screw-threaded portion adjacent head 21 whereon nut 23 may be screwed against the upper surface of said shield-plate, as shown in Figs. 2 and 4 of the accompanying drawings. Point 22 of pin 20 is adapted to provide a bearing-point upon the inside of the peak of cap 8 to support a shade embodying the present invention rotatably in place as shown in Fig. 2.

Fig. 5 illustrates a modified form of shade 30 of this invention adapted for use in connection with an electric bulb 4, said bulb being supported in an upright position by any suitable means with the nipple-point 24 of said bulb presented to the concavity of the peak of said cap 8 thus supporting said shade rotatably in place over said bulb. In this modified form, shield-plate 15, supporting member 16, pin 20, and nut 23 may be omitted in construction, as shown in said Fig. 5.

In operation, a shade embodying the present invention constructed according to the preferred form herein described, may be placed in position in connection with a candle as shown in Fig. 3, or a shade constructed in accordance with said modified form may be placed in position in connection with an electric bulb, as shown in Fig. 5, brake device 11 having, in either case, been moved to position away from the axis of pin 20 or nipple 24 as shown by position marked "A" in Figs. 1 and 6, whereupon the heat of the flame of candle 3 or of the light of bulb 4 will cause currents of air to strike propeller-blades 6 thus producing rotary motion of the shade, said shade rotating upon the point of said pin 20 or of said nipple 24, and cap 8 forming the bearing for said point 20 or for said nipple 24, being preferably hardened, as above-described, and being accurately formed, as shown in the accompanying drawings, said rotating motion will be a smooth, even motion, that will have a soothing effect upon persons watching same, and, moreover, said harden-

ing of cap 8 will provide a bearing of great durability against wear.

Should it be desired to stop the rotation of a shade of the present invention without extinguishing the light of candle 3 or of bulb 4, finger-piece 12 of brake device 11 may be moved toward pin 20 or nipple 24 to the position marked "B" in Figs. 1 and 6, whereby a portion of said device 11 adjacent pin 20 or nipple 24 may come in contact with said pin or said nipple, and may act as a frictional brake against rotary motion of said shade, said brake being locked in braking position, in the preferred form of brake device 11, Figs. 1, 2, 4, and 5, by means of a portion of the loop of said finger-piece 12 engaging an adjacent side of said opening 14, preferably the side of said opening nearest cap 8, and being held in said engagement under the spring-tension of said loop-shape. Reverse movement of finger-piece 12 to the position marked "A" Figs. 1 and 6 relieves the brake and again permits the shade to rotate, said brake device 11 being locked in said position "A," in said preferred form of said device, by means of the engagement of said spring-loop of finger-piece 12 with a side of said opening 14.

Among the advantages of a shade embodying the present invention is that it may be made collapsible and thus may be conveniently packed in a comparatively small space for shipment in quantities.

Various changes in the construction and arrangement of parts may be made without departing from the nature and spirit of the present invention.

I claim:

1. A rotatable shade for a light, said shade comprising a top and a skirt supported by said top, a plurality of propeller blades borne by said shade adapted to propel said shade by means of the action of air currents by the heat of said light, each blade being formed integrally with said shade, a bearing borne by said top over an appropriate opening in said top, said bearing having a peak and a lateral rim, means adapted to engage said rim, said means bearing a plurality of prongs adapted to secure said bearing to said top, and an axis supported above said light adapted to engage said bearing through said opening and adapted, also, rotatably to support said shade.

2. A rotatable shade for a light, said shade comprising a top and a skirt supported by said top, a plurality of propeller blades borne by said shade adapted to propel said shade by means of air currents caused by the heat of said light, means adapted rotatably to support said shade axially about said light, a member borne by said top adapted releasably to engage an adjacent portion of said axial support to brake and arrest the rotary motion of said shade.

- 4 shade, means borne by said top adapted to limit the movement of said member toward said axial support, said member having one end pivotally attached to said top, and 5 means borne by the other end of said member adapted to engage said limiting means.
3. In a rotatable shade for a light, the combination with a hollow member having a top and an open bottom adapted to be 10 rotatably supported axially about said light, of means borne by said top adapted releasably to engage an adjacent portion of the axial support of said member to brake and arrest the rotary motion of said member.
- 15 4. In a rotatable shade for a light comprising a hollow member adapted to be rotatably supported axially about said light, rotary motion being imparted to said member by the action of air currents caused by 20 the heat of said light, the combination with a top for said hollow member, said top having a central opening, of a bearing borne by said top over said central opening, said bearing consisting of a hollow peak having a laterally extending base-rim, an annular member adapted to rest upon said base-rim, said annular member having a plurality of prongs adapted to pierce said top and adapted, also, to hold said rim with 25 said annular member upon said rim adjacent the surface of said top, an axis having an end adapted to bear upon the concavity of the peak of said bearing through said cen-
- tral opening rotatably to support said hollow member, means borne adjacent the base 35 of said light and extending upwardly therefrom adapted rigidly to support said axis, a member borne by said top adapted releasably to engage an adjacent portion of said axis to break and arrest the rotary motion 40 of said hollow member, one end of said braking member being pivotally attached to said top, and means borne by said top adapted to limit the movement of said 45 brake-member toward and away from said axis, portions adjacent the other end of said brake-member being adapted to engage said limiting means.
5. In a rotatable shade for a light, the combination with a hollow member having a top and an open bottom adapted to be 50 rotatably supported about said light, of means borne by said top adapted releasably to engage an adjacent portion of the axial support of said member to brake and arrest 55 the rotary motion of said member, and means rigidly borne by said axial support adapted to shield said member from the flame of the shaded light.

In testimony whereof I hereunto affix my 60 signature in the presence of two witnesses.

YUKINOBU YAMAMOTO.
